UNITED STATES PATENT OFFICE.

SAMUEL P. HULL, OF YONKERS, NEW YORK.

FRONT ROD.

Application filed April 11, 1924. Serial No. 705,808.

This invention relates to railway tracks more particularly to the switches and especially to what are known as front rods and lugs therefor.

5 The principal object of this invention is to provide a front rod and connections to switch points such that in use there will be practically no opportunity for lost motion to develop and which will rigidly support the 10 points so that they will fit close up to the stock rail and will facilitate the throwing and forcing of the switch point to its proper position by a decreased amount of force.

Other objects and advantages will appear 15 as the description of the particular physical embodiment selected by applicant to illustrate the invention progresses and the novel features of the invention will particularly be pointed out in the appended claims.

20 In describing the invention in detail, and the particular physical embodiment selected to illustrate the invention reference is had to the accompanying drawing, wherein I have 25 illustrated a particular preferred physical embodiment of my invention, and wherein like characters of reference designate corresponding parts throughout the several views, and in which:

Figure 1 is a top plan view of a switch 30 lay out with my invention applied thereto; Fig. 2, is a top plan detail view of my improved front rod and switch lug; Fig. 3 is an elevational view of my improved front rod and switch lug.

35 As is well understood by those skilled in the railway art it is essential that a switch point shall bear closely and firmly against the rail toward which it is thrown and that after having been thrown and locked it 40 must remain in the proper position so that a wheel passing the switch point will have no chance whatsoever to enter between the rail and the switch point in case the switch point is thrown up against the rail. It is also well 45 known to those skilled in the railway art that the ordinary lock rod connected to the front rod of a switch is pierced in two places and the hole therein is but very slightly larger than the plunger of the lock which 50 must enter the hole when the switch is thrown to lock the switch in the thrown position, so that in order to be able to pass the lock of the plunger lock through the lock rod, it is necessary that the switch points be

in perfect adjustment with no loose connecting parts whatsoever. It is also well known that in many types of switch rods there are bolts connecting the switch lug with the front rod and there is a slight turn-movement on these bolts due to the fact that the angle between the switch point and a front rod changes slightly as the switch is thrown from one side to the other as is well understood by those skilled in this art. This slight turning movement along with vibration causes wear and in time a looseness which at times is so excessive that the switch may be fully thrown but, due to the lost motion in the front rod, the lock rod will not be properly positioned so that the lock 70 plunger may enter the proper orifice therein so that it is necessary when such a switch is operated from an interlocking tower to send a man out on the ground and adjust the parts. Such a difficulty is realized by those 75 skilled in this art to be very serious because if the lock plunger cannot be thrown the signals controlling movements over the interlocked switch cannot be operated to move them to the safe position although the 80 switch is in proper position to be passed over.

Applicant's construction is particularly designed to obviate the well known defects hereinbefore pointed out and to be thrown 85 and forced up against the stock rail in proper position for a train movement there-over with considerable less exercise of physical force than with the types now commonly used.

90 In Figure 1, numeral 1 indicates one rail and numeral 2 another rail of a trackway and 3 designates one switch point and 4 another switch point of a switch for guiding trains either along the main line or to the 95 siding. These rails and switch points may be and are intended to be illustrated as of common and ordinary construction and are supported by ties as 5 and 6 in the usual and customary manner and the switch points 100 are thrown by the ordinary and well known throw rod 7. L designates a plunger lock having a plunger 8 which is moved in the usual and well known manner as from an interlocking tower by any suitable form of 105 connection and in one position of the switch is intended to pass through the orifice 9 and in another position of the switch is intended

to pass through an orifice 10 in a lock rod 11. The lock rod and lock are merely illustrative of old and well known practice.

- The front rod for the switch designated as 5 a whole S in the construction shown includes two bar like members as 12 and 13 rigidly connected end to end by the fish plates 14 and 15, one 14, also serving as a bracket to which the lock rod 11 is attached.
- 10 In the form of front rod shown there is insulating material 16 positioned between the ends of the two portions of the front rod and between the front rod and the fish plates 14 and 15 and there are insulating ferrules 15 or sleeves as 17 surrounding the bolts as 18 so that one part 12 of the front rod is insulated electrically from the other part 13 of the front rod. This form of front rod is shown as a preferred form but it is to be 20 understood that applicant's invention is not confined in its use to such form of front rod and it will be understood to those skilled in the art as the description progresses, that the essential principle of applicant's invention is equally applicable to other and 25 usual forms of front rods sectional or non-sectional.

On each end of the front rod, designated as a whole by F, is applicant's improved 30 switch lug which serves to connect the ends of the front rod to the two points as 3 and 4 of the switch S. These lugs are identical in construction except that one is right handed and the other left handed. The 35 switch lugs, as more clearly shown by Fig. 2, consist of a plurality of plate like members as 19, 20, and 21. These plates are preferably formed of metal and preferably of rolled steel. The plates are parallel one to 40 the other throughout their entire length and each is bent intermediate its end so as to form a right angle and by reference to Fig. 3 it will be seen that each of the plates is bent in another plane so that its legs are at 45 an angle one to the other. The plates are suitably orificed as at 22 and 23 and also at 24, 25 and 26. One of the legs of a switch lug designated as a whole by M lies parallel to and against one section of the front rod and 50 is attached thereto in any desirable or appropriate means as by rivets 27 passing through the orifices 24, 25 and 26 and through corresponding orifices formed in the section as 12 of the front rod. The other 55 leg of the switch lug M is attached to a switch point as 3 as shown in Fig. 1 preferably by bolts as 28, which are passed through the orifices as 22 and 23 and through corresponding orifices in a switch 60 point as 3.

The front rod constructed as herein described is practically equivalent in so far as lost motion is concerned to a solid front rod as the connection between the two sections 65 12 and 13 of the front rod may be made as

rigid and everlasting as though the front rod were made in one piece, that is, section 12 and 13 were one. The connections formed by rivets as 27 can be made so firm and rigid that no action can possibly take place between section as 12 and a switch lug as M. There is, therefore, no opportunity for wear as in many of the common types of front rods which provide a means whereby the angle between a front rod as F and a switch 70 point as 3 may change as the switch point is thrown back and forth by oscillating motion on a bolt attaching the switch lug to the front rod. There being no motion between the parts in applicant's construction there is no opportunity for wear and therefore no lost motion will develop to prevent a switch from being properly locked after being properly thrown. Applicant's construction of switch lug is such that it is flexible in a horizontal plane but practically rigid in a vertical plane, that is, the switch lug M as shown in Fig. 2 may bend slightly in both directions as shown by double arrow 29 but it practically completely resists force tending to change the angle of the face 30 with a horizontal plane, that is, it maintains the switch point 3 in its proper upright position and does not allow the top extreme corner 31 thereof to top away from the rail 1. The 80 fact that applicant's switch lug is flexible in one plane facilitates the throwing and proper holding and forcing of a switch point up against the stock or main rail and the fact that applicant's switch lug is rigid so as to prevent overturning of the switch point means that the switch point at its upper portion, the important portion, will always lie in the exact proper position.

In the particular construction shown by applicant the flexibility in a horizontal plane and the rigidity or inflexibility in a vertical plane has been obtained by constructing the switch lug M of parallel plate like members and introducing a bend intermediate the ends. This bend is intermediate the points of attachment to the switch and to the rod, as 12, and particularly this horizontal flexibility centers in a vertical line between the corner 31 of the switch 3 and the rod 12 and is preferably as closely adjacent the corner 31 as possible. Although the construction as above set forth is preferred, it is desired to have it understood that the principle underlying the invention does not negative the exhibition thereof in other construction and does not exclude constructions in which the flexibility is obtained by such expedients as reduces cross sectional areas at a part or parts of the switch lug.

The fact that applicant's switch lug is flexible in one plane gives it an advantage over a solid front rod and solid switch lug rigidly attached thereto in that less force is required to throw switches equipped with

applicant's improved construction than with a solid front rod and solid lug rigidly attached thereto of the prior construction. This advantage in favor of applicant's construction means that a saving of about one hundred pounds is effected in the force required to throw a switch.

Although I have particularly described the construction of one physical embodiment 10 of my invention and explained the operation and principle thereof, nevertheless, I desire to have it understood that the form selected is merely illustrative but does not exhaust the possible physical embodiments of the 15 idea of means underlying my invention.

What I claim as new and desire to secure by Letters Patent of the United States, is:

1. A switch lug formed of a plurality of stacked plates.
2. A switch lug formed of a plurality of plates bent intermediate their ends to form approximately a right angle.
3. A switch lug formed of a plurality of plates bent intermediate their ends to form approximately a right angle and one leg bent in another plane at an angle to the other leg.
4. A front rod for railway switch points including a rigid bar like member having fixedly attached at one end a switch lug formed of a plurality of parallel plates formed with two legs, one lying parallel to

and attached to the bar like member and the other bent at approximately a right angle thereto for attachment to a switch point.

5. A front rod for a railway switch having two points including a rigid bar like member having fixedly attached at each end a switch lug formed of a plurality of parallel plates formed with two legs, one lying parallel to and attached to the bar like member and the other bent at approximately a right angle thereto for attachment to a switch point.

6. A front rod for a railway switch, in combination: two bar like members insulatingly attached end to end and switch lugs each formed of a plurality of plate like members formed with two legs one lying parallel to and attached to each free end of the bar like members and the other at approximately a right angle thereto for attachment to a switch point.

7. As an article of manufacture a flexible switch point lug formed of a plurality of parallel plates.

8. A front rod for a switch rigid in a vertical plane and having substantial flexibility in a horizontal plane.

9. A front rod for a switch formed with a bend and rigid in a vertical plane and flexible at the bend in a horizontal plane.

SAMUEL P. HULL.
